UNITED STATES PATENT OFFICE.

HIRAM B. WINTER, OF CLARKSBURG, WEST VIRGINIA.

GOODS-HANDLING DEVICE.

1,109,730.

Specification of Letters Patent.

Patented Sept. 8, 1914.

Application filed February 4, 1914. Serial No. 816,555.

To all whom it may concern:

Be it known that I, HIRAM B. WINTER, a citizen of the United States, residing at Clarksburg, in the county of Harrison and 5 State of West Virginia, have invented certain new and useful Improvements in Goods-Handling Devices, of which the following is a specification, reference being had to the accompanying drawings.

10 This invention has for its primary object a simple, durable and easily operable device for handling cans or bottled goods and particularly for removing the cans or bottles from high shelves without the necessity of 15 the operator standing upon a counter, chair, ladder, or other similar device.

A further object of the invention is a device of this character which can be cheaply manufactured and easily assembled, and in 20 which the parts are so arranged that they will grasp a can, for example, practically in an automatic or self-acting manner, requiring practically no effort on the part of the operator to move the clamping bars to their 25 operative clamping position. And the invention also aims to generally improve devices of this character so as to render them more useful and commercially desirable.

With these and other objects in view, as 30 will more fully appear as the description proceeds, the invention consists in certain constructions, arrangements and combinations of the parts that I shall hereinafter fully describe and claim.

35 For a full understanding of the invention, reference is to be had to the following description and accompanying drawing, in which—

Figure 1 is a rear elevation of my improved goods handling implement, partly broken away to indicate that the handle or standard may be of any desired length. Fig. 2 is a view similar to Fig. 1, but showing the jaws open. Fig. 3 is a sectional view 45 on the line 3—3 of Fig. 2. Fig. 4 is a detail section of one of the guides for actuating the rod, and Fig. 5 is a fragmentary perspective view illustrating one of the clamping bars and its jaw and a link pivotally connected thereto.

Corresponding and like parts are referred to in the following description and designated in all the views of the accompanying drawing by like reference characters.

50 My improved device for handling cans and bottled goods and the like includes a

pole of standard 1 preferably made of wood, and of any desired length and width and thickness, the standard being preferably provided at one end with an enlarged or laterally widened head portion 2. A substantially U-shaped metallic strap 3 is secured to the end of the head portion 2 by fastening devices of any desired character, the laterally extending ends of the strap 3 being twisted or given a quarter turn, as clearly indicated at 4, and being pivotally connected to metallic clamping bars 5, of any desired length. The bars 5 are turned laterally at their free extremities to form 70 curved jaws 6 adapted to fit around and embrace the body portion of a bottle or can, for example, said jaws being preferably lined with rubber or some similar substance, so as to assist in maintaining a firm grip 75 upon the article grasped.

Intermediate of their ends the clamping bars 5 have links 7 pivotally connected thereto at one end, the links being pivotally connected together at their other ends, as 80 indicated at 8. Where the links 7 are pivotally joined together, they have secured to them one end of an actuating rod 9 which extends along the handle, as clearly illustrated in the drawing and is held in position 85 for longitudinal movement by passing through apertured ears or guides 10 and 11. The guides 11 at the lower end or foot of the standard 1 are preferably of the spring type designed to permit an easy longitudinal 90 movement of the actuating rod 9, but at the same time hold said rod wherever it is moved so as to prevent any accidental movement. Preferably the rod is provided at its lower end with a foot piece or knob 12. 95 It is to be particularly noted that the rod 9 is longer than the standard 1, for a purpose to be hereinafter specified. The clamping bars 5 are also connected together intermediate of their ends and preferably below 100 the link bars 7 by means of a contractile coiled spring 5^a.

From the foregoing description in connection with the accompanying drawing, the operation of my improved article handling 105 device will be apparent. In the practical use of the device, the jaws are opened by moving the rod 9 in the required direction to bring the link bars 7 into alinement with each other and thereby swing the clamping 110 bars 5 outwardly or away from each other, and the alinement of the link bars either

alone or in connection with the spring guides 11 will hold the jaws in open position as long as required. In order to remove a can, for example, from a high shelf or other elevated place, it is only necessary for the operator to grasp the handle or standard 1 with the jaws in their open position and to cause the jaws to extend on opposite sides or embrace the article it is desired to remove 10 from the shelf. Then only a slight movement of the rod 9 is sufficient to "break the joint" of the link bars 7, whereupon the contractile spring 5^a will be permitted to act and the clamping bars 5 will be brought together and the jaws 6 securely clamped upon the can. After the can has been brought 15 down to a convenient position where it can be removed by the operator's hand, the preferred operation in releasing the jaws from the can is for the operator to press the lower end of the device down upon the floor and as, in the closed position of the jaws, the lower end of the rod projects below the lower end of the handle or standard 1, it is 20 clear that this downward pressure will tend to move the rod upwardly and spread the jaws apart and allow the can to be very easily removed therefrom. To secure this result, it is only necessary that the actuating 25 rod 9 be of such length that its lower end will project below the lower end of the handle or standard 1 when the jaws are in their operative or substantially closed position.

While the accompanying drawing illustrates what I believe to be the preferred embodiment of my invention, it is to be understood that the invention is not limited thereto but that various changes may be made 35 in the construction, arrangement, and proportions of the parts without departing 40 from the scope of the invention, as defined in the appended claim.

What I claim, is:

A goods handling device comprising a 45 pole or handle provided at its upper end with an enlarged head, an approximately U-shaped strap secured to the upper end of the head and having its ends bent on a quarter turn and disposed at right angles to the attached portion to provide ears, a pair of clamping bars having their lower ends pivoted to the ears and their upper ends bent outward at right angles to the length of the bars and curved to provide jaws, a link pivoted to each of the bars, guides secured to the pole, an actuating rod engaging the guides and having one end projecting beyond the smaller end of the pole and its other end pivotally connected with the links, 50 and a retracting spring connected with the clamping bars below the links.

In testimony whereof I hereunto affix my signature in the presence of two witnesses.

HIRAM B. WINTER.
